UNITED STATES PATENT OFFICE.

JOHANN STUMPF, OF CHARLOTTENBURG, GERMANY, ASSIGNOR TO
GENERAL ELECTRIC COMPANY, A CORPORATION OF NEW YORK.

STEAM OR GAS TURBINE.

SPECIFICATION forming part of Letters Patent No. 794,898, dated July 18, 1905.

Application filed September 8, 1903. Serial No. 172,244.

To all whom it may concern:

Be it known that I, JOHANN STUMPF, a subject of the King of Prussia, German Emperor, and a resident of 27 Rankestrasse, Charlottenburg, near Berlin, Kingdom of Prussia, German Empire, have invented certain new and useful Improvements in Steam or Gas Turbines, of which the following is an exact specification.

10 My invention relates to improvements in steam or gas turbines, and more especially to a device for regulating the steam admission of the same; and it has for its purpose to provide a device by means of which it is attained 15 that the steam admission can be regulated by means of a centrifugal pump coupled to the turbine. I attain this purpose by the construction illustrated in the accompanying drawings, in which—

20 Figure 1 shows the turbine provided with my new device, partly in section and partly in diagrammatic view. Fig. 2 shows a modification of part of the device shown in Fig. 1. Fig. 3 is a sectional detail view showing a 25 nozzle for admitting motive fluid to the wheel-buckets. Fig. 4 shows a similar construction, wherein the nozzles are arranged in groups.

The construction forming the object of the 30 present invention is based upon the fact that in the casing of the centrifugal pump a pressure arises which varies according to the velocity of the impeller. This pressure, which occurs chiefly at the circumference of the impeller, is used, according to the present invention, for 35 regulating the steam admission by moving, by means of this pressure, a piston or the like, which in the well-known manner successively cuts out or inserts single steam-admission nozzles or groups of the same.

40 In the examples shown in the drawings, *a* is the turbine proper. *b* is the shaft of this turbine.

c is the impeller of a centrifugal pump. *d* is the casing of this pump.

45 *e* represents the nozzles for the steam admission to the turbine-wheel. The nozzles *e* are connected, by means of steam-conduits *f*, with the cylinder *g*. It will be seen from the drawings that the ends of the steam-conduit *f*

are situated in the cylinder *g* at different 50 heights.

h is a piston situated in the cylinder *g*, by means of which piston the steam-conduits *f* can be opened and closed. Above the cylinder *g* a second cylinder *i* is arranged, in which 55 a piston *k* is situated. The pistons *k* and *h* are connected to each other by the piston-rod *l*. To the cylinder *i* springs *m* are fixed, which connect the cylinder with the cross-bar *m'*, fixed to the piston-rod *l*. The springs *m* 60 tend to draw the piston-rod, with the two pistons *k* and *h* fixed to the same, upward. The cylinder *i* is connected, by means of a pipe *n*, with the casing *d* of the centrifugal pump. The lower part of the cylinder *i* is connected, 65 by means of a pipe *n'*, to a reservoir *n''*. This reservoir *n''* is connected, by means of a pipe *n'''*, to the casing *d* of the centrifugal pump. It will thus be seen that the fluid is caused to move in cycle by virtue of the rotation of the 70 impeller *c* and the parts connected therewith.

The effect of the device is as follows: The 75 pump-casing, as well as the upper part of the cylinder *i*, is filled with a liquid—for instance, with oil. According to the velocity with which the turbine-wheel and the impeller *c*, coupled with the same, rotate a lower or higher pressure will prevail in the casing *d*. This pressure will act upon the piston *k*, so that the position of this piston will be changed by the 80 number of revolutions of the turbine being changed. By the position of the piston *k* being changed the position of the piston *h* will also be changed, and it is hereby attained that as soon as the number of revolutions of the 85 turbine are increased the piston *h* is pressed downward, and thereby closes one or several steam-conduits *f*, so that the steam admission is diminished and the number of revolutions of the turbine reduced. The steam enters the 90 cylinder *g* through the pipe *g'*. The oil which is pressed through between the piston *k* and the cylinder *i* flows through the pipe *n'* into the reservoir *n''* and can flow back from there through the pipe *n'''* to the centrifugal pump. 95

It will be understood that the device for closing the steam-conduits by the movement of the piston *k* may be constructed in any con-

venient manner—as, for instance, in Fig. 2 a construction is shown in which a cylinder σ is provided, the bottom σ' of which is step-formed. Each step is provided with one or 5 several openings, to which the steam-conduits f (shown in Fig. 1) are connected. The openings are closed by means of valves p , the valve-rods of which are provided with stops p' , situated at different heights. q is a disk 10 provided with holes in which the valve-rods are guided. The effect of this device is similar to the effect of the device described in connection with Fig. 1. If the pressure above the piston k surpasses certain limits—that is 15 to say, if the number of revolutions of the turbine increases—the piston k and the disk q , connected to the same, are pressed downward against the effect of the spiral springs m . By the disk q being pressed downward 20 the several openings in the bottom σ' will gradually be closed, thereby closing the steam-conduits f and diminishing the steam admission.

In Fig. 3, e' represents the nozzle-plate, 25 containing the nozzle orifices or passages e , which may be of any suitable construction. Motive fluid is supplied to these nozzles from a fluid-containing chest e^2 , which in turn is connected by the pipes f with the cylinder g . 30 r' represents a row of buckets adjacent to the discharge ends of the nozzles, and r' a row of buckets receiving motive fluid from the buckets r . As many rows of these buckets are provided as are necessary to abstract the energy 35 from the motive fluid. They may all rotate, or some may be stationary and others rotary.

Fig. 4 a similar construction is shown, except that the nozzles are arranged in groups, so that a single pipe f supplies fluid to two or 40 more nozzle-passages.

Having thus fully described the nature of this invention, what I desire to secure by Letters Patent of the United States is—

1. In a steam or gas turbine, the combination 45 of the turbine proper with several steam-conduits, a centrifugal liquid-pump coupled to the turbine, a cylinder connected to the liquid-pump, a piston situated within the cylinder and acted upon by the fluid from the 50 pump and means for closing the steam-conduits successively by the movement of said piston.

2. In a steam or gas turbine regulator, the combination of a turbine having a plurality of 55 steam-conduits, a pump actuated by said turbine, and means actuated by the pressure from the pump for controlling said plurality of steam-conduits successively.

3. In a steam or gas turbine regulator, the 60 combination of a turbine, a plurality of steam-conduits for said turbine, a pump actuated by said turbine, means for controlling said conduits, and means for communicating the pressure of the pump-casing to said controlling 65 means for moving it.

4. In a regulator for steam or gas turbines, the combination of a steam-turbine, a plurality of steam-admission conduits therefor, a centrifugal pump actuated by said turbine, a cylinder in direct communication with the pump-casing and means actuated by the pressure in said cylinder for controlling the flow of steam to said conduits. 70

5. In a regulator for steam or gas turbines, the combination of a turbine, steam-admission 75 conduits for said turbine, a pump actuated by said turbine, a cylinder in direct communication with the pump-casing, a valve device responding to pressure changes in the cylinder for controlling the flow of steam to said conduits successively. 80

6. In a regulator for steam or gas turbines, the combination of a turbine, a plurality of steam-admission conduits for said turbine, a plurality of valves for controlling said conduits, and means for controlling said valves successively. 85

7. In a regulator for steam or gas turbines, the combination of a turbine, a plurality of steam-admission conduits for said turbine, a 90 valve-casing, a plurality of valves in said casing for controlling said conduits successively, and a pressure-actuated device for controlling said valves.

8. In a regulating device for motors and engines, the combination with a rotary part driven by the motor or engine, a fluid subjected to pressure and caused to move in cycle by virtue of the rotation of said part, separate conduits for conveying motive fluid to the rotary part, and means for causing said fluid under pressure to change the quantity of the driving medium passing to and into the motor or engine by changing the number of conduits in service. 95

9. In a regulating device for motors and engines, the combination with a rotary part driven by the motor or engine, a liquid subjected to pressure and caused to move in cycle by virtue of the rotation of said part, separate conduits for conveying motive fluid to the rotary part, means for changing the quantity of the driving medium passing to and into the motor or engine by successively cutting the conduits into and out of the service, 100 and means for causing said liquid under pressure to operate said first-mentioned means. 105

10. In a regulating device for motors and engines, the combination with a rotary part driven by the motor or engine, a liquid subjected to pressure by virtue of the rotation of said part, a plurality of individual conduits for conveying motive fluid to the rotary part, means for changing the quantity of the driving medium passing to and into the motor or 110 engine by cutting the conduits into and out of service successively, and means for causing said liquid under pressure first to operate said first-mentioned means and then to return to the said rotary part. 115

120

125

130

11. In a regulating device for motors and engines, the combination with a rotary part driven by the motor or engine, a liquid subjected to pressure and caused to move in cycle by virtue of the rotation of said part, a plurality of individual conduits for conveying motive fluid to the rotary part, means for changing the quantity of the driving medium passing to and into the motor or engine by cutting the conduits into and out of service successively, means for causing said liquid under pressure to operate said first-mentioned means, and a pipe for leading the liquid under pressure to the means mentioned in the second place.
12. In a regulating device for motors and engines, the combination with a rotary part driven by the motor or engine, a liquid subjected to pressure by virtue of the rotation of said part, a pipe adapted to receive said liquid under pressure, a cylinder connected with said pipe, a return-pipe from cylinder to the rotary part, a piston in said cylinder, means comprising separate conduits which are opened

and closed successively for changing the quantity of the driving medium passing to and into the motor or engine, and means for said piston to operate said first-mentioned means.

13. In a governing mechanism for elastic-fluid turbines, the combination of a pump driven by the turbine for creating a fluid-pressure independent of the motive fluid, the amount of which is dependent upon the speed of the turbine, with a regulator for varying the admission of motive fluid to the turbines by cutting nozzles into and out of service which is actuated directly by the fluid from the pump and moves to and fro as the pressure of the fluid from the pump rises or falls.

In testimony whereof I have signed my name to this specification in the presence of two subscribing witnesses.

JOHANN STUMPF.
